IRONER FOR SMOOTHING CLOTHING, LINENS OR THE LIKE

George Schwartz, New York, N.Y. (1031 Orion Court, East Meadow, N.Y. 11554)

Filed Apr. 5, 1966, Ser. No. 1,788

Term of patent 14 years

(Cl. D49—6)

FIG. 1

FIG. 2

FIG. 4

FIG. 5

FIG. 3

FIG. 1 is a top plan view of an ironer for smoothing clothing, linens or the like, showing my new design;

FIG. 2 is a front elevational view thereof;

FIG. 3 is a bottom plan view thereof;

FIG. 4 is a side elevational view thereof; and,

FIG. 5 is a side elevational view of the opposite side from that shown in FIG. 4.

I claim:

The ornamental design for an ironer for smoothing clothing, linens or the like, as shown.
